US00D850096S

(12) **United States Design Patent** (10) **Patent No.:** **US D850,096 S**
(45) **Date of Patent:** **** Jun. 4, 2019**

(54) **BASE FOR A TRIPOD CANE**

(71) Applicant: **Drive Medical Design & Manufacturing**, Port Washington, NY (US)

(72) Inventor: **Garrett Kaplan**, Port Washington, NY (US)

(73) Assignee: **MEDICAL DEPOT, INC.**, Port Washington, NY (US)

(**) Term: **15 Years**

(21) Appl. No.: **29/565,600**

(22) Filed: **May 23, 2016**

(51) **LOC (11) Cl.** **03-01**

(52) **U.S. Cl.**

USPC **D3/11**

(58) **Field of Classification Search**

(57) **CLAIM**

The ornamental design for a base for a tripod cane, as shown and described.

DESCRIPTION

FIG. 1 is a perspective top view of a base for a tripod cane of the new design;

FIG. 2 is a top view thereof;

FIG. 3 is a bottom view thereof;

FIG. 4 is a front view thereof;

FIG. 5 is a side view thereof;

FIG. 6 is a back view thereof; and,

FIG. 7 is a perspective bottom view thereof.

The broken lines depict portions of the article that form no part of the claimed design.

1 Claim, 3 Drawing Sheets
